UNITED STATES PATENT OFFICE.

EDWARD A. STINSON, OF FRANKFORT, INDIANA, ASSIGNOR OF ONE-HALF TO MILTON T. McCARTY, OF FRANKFORT, INDIANA.

COMBINATION-FUEL CARBURETER.

1,211,003

Specification of Letters Patent.

Patented Jan. 2, 1917.

Application filed January 8, 1916. Serial No. 71,013.

To all whom it may concern:

Be it known that I, EDWARD A. STINSON, a citizen of the United States, residing at Frankfort, in the county of Clinton, State of Indiana, have invented certain new and useful Improvements in Combination-Fuel Carbureters; and I do hereby declare the following to be a full, clear, and exact description of the invention, such as will enable others skilled in the art to which it appertains to make and use the same.

This invention relates to carbureters for internal combustion engines and has for its object to provide a carbureter so arranged as to supply a number of different fuels to the engine either in combination or singly.

A particular object is to provide a carbureter which will supply, for instance, gasoline or kerosene and which will include means for shifting from one fuel to the other gradually or for supplying varied combinations of the two fuels.

In the drawings:—Figure 1 is a plan showing the present carbureter applied to an engine and illustrating the arrangement of the auxiliary air vane with respect to the cooling fan; Fig. 2 is a top view of the carbureter with the top plate removed, partly in section; Fig. 3 is a longitudinal section on line 3—3 of Fig. 2 taken through the fuel web; Fig. 4 is a fragmentary section on line 4—4 of Fig. 2 through the plunger valve chambers, the top plate and double valve lever being shown in position; Fig. 5 is a section on line 5—5 of Fig. 2 in detail, through the water duct web; Fig. 6 is a detail section on line 6—6 of Fig. 3 with the floats and valve housings removed; Fig. 7 shows a modified form of auxiliary air valve using a spring which provides for automatic admission of extra air under the action of the engine; Fig. 8 is a section through the mixing dome on line 8—8 of Fig. 3; Fig. 9 is a section on line 9—9 of Fig. 3 to show the fuel duct, and Fig. 10 is a detail plan showing a part of the auxiliary air valve.

Referring now to the drawings, the present invention comprises a hollow bowl 10 which has cast integrally therewith and centrally thereof a sleeve 11, the passage 12 of which is carried through the bottom of the bowl. A top plate 13 is secured upon the bowl and has a central opening 14 registering with the passage 12 through the sleeve so that there is thus formed a passage ex-

tending through the bowl from the top to bottom.

Cast within the bowl and integral therewith there are three radial webs indicated at 15, 16 and 17 respectively, these webs dividing the bowl into three separate compartments 18, 19 and 20. The web 16 which separates the compartments 18 and 20 is thickened, as shown, to accommodate fuel ducts 21 and 22 and a horizontal chamber 23. The chamber 23 opens at one end through the outer face of the bowl and at the other end through a projection 24 formed on the inner face of the sleeve 11 opposite the web 16, and there is a valve seat 25 within this opening.

The fuel ducts 21 and 22 open through the valve seat, 25, and the ducts are led downwardly and outwardly within the web 16 to communicate at their outer ends with plunger valve chambers 26 and 27 formed vertically and parallel to each other in enlargements 28 formed at the outer end of the web 16. These enlargements lie in the compartments 18 and 20, as shown, and at the bottoms of these chambers 26 and 27, there are valve seats 26' and 27' above the points of communication of the ducts with the chambers. It will be understood that the ducts 21 and 22 are formed by drilling in from the outer face of the bowl 10, and by drilling down from the chambers 26 and 27, the openings through the face of the bowl being closed by plugs A. There are passages 29 and 30 which also communicate with the chambers 26 and 27 and which communicate respectively with the compartments 18 and 20, these passages, of course being formed through the enlargements 28 and opening through the valve seats 26' and 27'. It will thus be seen that there is communication through the web 16 and its enlargements between the single outlet of the chamber 23 and both the compartments 18 and 20. A needle valve 31 is threaded into the chamber 23 and, seating against the valve seat 25, will control the passage of fluid from the two compartments 18 and 20.

In the valve chambers 26 and 27 there are disposed plunger valves 32 and 33, these valves being arranged to enter the valve seats 26' and 27' and thus close the ducts 21 and 22. These two plunger valves are normally held away from their seats by springs 34 engaging at one end against shoulders 35 formed within the plunger

valve chambers and at their other ends against enlarged heads 36 carried by the upper ends of the valves.

The top plate 13 is provided with openings 13' which register with the upper ends of the plunger valve chambers 26 and 27 and the upper ends of the plunger valves project through these openings 13'. Mounted upon the top plate adjacent to these openings 10 there is a block 37 carrying a horizontally extending shaft 38 extending above the top plate and in a line between the two openings 13'. This shaft has a lever 39 mounted thereon, the lever including two arms 40 and 41 projecting oppositely and over the upper ends of the two plunger valves 32 and 33, the valves being held in engagement with these arms by the springs 34, as shown. An arm 42 extends upwardly 15 from the lever 39 and is adapted to receive any suitable connection by means of which the lever may be rocked upon the shaft 38 in either direction.

Within the sleeve 11 there is engaged an 20 air conducting tube 43, this tube resting against the projection 24 of the sleeve 11 and having an opening 44 therein which registers with the opening of the chamber 23.

From the foregoing it will be observed 25 that as the lever 39 is rocked to depress the arm 40, the plunger valve 32 will be depressed through its engagement by the arm 40 and, the arm 41 rising, the plunger 30 valve 33 will rise under the action of its spring 34. One of the plunger valve rises as the other is depressed and vice versa. This will result in the gradual cutting off 35 of communication between the compartment 40 and the tube 43 of the sleeve and the gradual establishment of communication 40 between the compartment 18 and the tube 43, the cutting off of one corresponding exactly to the establishment of 45 the other, and with fuels of two different kinds in the two compartments, such as gasoline and kerosene, it will be seen that either of these fuels may be admitted to the tube 43, or a mixture of both fuels may 50 be admitted and that the proportion of the fuels in such mixture may be controlled to the finest point.

It is stated in the foregoing that: "One 55 of the plunger valves rises as the other is depressed and vice versa"; and in this statement the word "as" is used in the sense in which it is used in the science of physics to mean "in exact proportion." Whenever the word as is used in the appended claims 60 with reference to the relative operation of the valves 32 and 33 it is to be understood as having this meaning.

The lower end of the tube 43 carries a 65 mixing dome 45 which is connected with the tube by means of webs 46 carried by

the flared lower end 47 of the tube, this flared end lying within the dome 45 as illustrated. There is an opening between the tube 43 and the dome 45, this opening being indicated at 48 and communicating with the passage 12 exteriorly of the tube 43. It will be seen that the tube 43 is held in spaced relation to the inner surface of the sleeve 11 by the projection 24 and by additional projections 24'. There is thus an air passage 12 from the top of the device into the vaporizing dome 45 exteriorly of the tube 43 to conduct auxiliary air as will be later set forth.

The tube 43 and the vaporizing dome 45 are held in place by a sleeve 49 threaded upon the upper end of the tube above the top plate 13 and having a flange 50 formed at its lower end. This flange has a chamber 51 formed in its under face, and it is the resultant edge portion 52 which rests against the top plate 13 to hold the parts together. As will be seen, the chamber 51 communicates with the passage 12 exteriorly of the tube 43, and there are openings 53 formed through the flange 50 and communicating with the chamber 51 for the admission of auxiliary air. Revolubly engaged upon the sleeve 49 there is a second sleeve 54, this sleeve carrying a flange 55 which is disposed upon the flange 50 and which is provided with openings 56 which may be brought into and out of registration with the openings 53, by oscillation of the sleeve 54 upon the sleeve 49. A spring 57 is connected with the flange 55 and is arranged to hold it normally with its openings out of registration with the openings 53, this spring being suitably anchored as illustrated. A vane 58 is carried by the sleeve 54 and extends laterally therefrom for a purpose which will be brought out in the statement of the operation of the device.

Within the tube 43 there is a tube 59 formed of wire gauze, and this gauze tube 110 extends through the flared end 47 of the tube and into the mixing dome 45 resting at its lower end against the inner face of the dome.

One of the projections 24' is located opposite the inner end of the web 15 of the bowl, and formed through this projection and within the web 15 there is a duct 60 which leads downwardly through the web to communicate with a vertical needle valve chamber 61 formed at the outer end of the web. There is a valve seat 61' at the lower end of this chamber through which the duct 60 opens and there is a passage 62 formed through the web which communicates with the needle valve chamber 61 and with the compartment 19 of the bowl. A needle valve 63 is threaded into the chamber 61 for engagement of its valve point against the seat 61'. The tube 43 has an opening 64 therein 130

which registers with the inner end of the duct 60 so that fluid passing from the compartment 19 through the duct 60 will be led into the tube 43 in the same manner as fluid from the compartments 18 and 20 is led into the tube 43 through the ducts 21 and 22, and the opening 44.

It will be noted that the gauze tube 59 will receive fluid admitted to the tube 43 through both its openings 44 and 64 and that such fluid will saturate the gauze tube under the action of both gravity and capillary attraction.

To supply each of the compartments 18, 15 19 and 20 with fluid, openings 65 are formed in the wall of the bowl and these openings communicate with passages 66 formed in bosses 67 cast upon the bottoms of the several compartments. These bosses have central 20 interiorly threaded circular apertures 68 in their upper faces and communicating with the passages 66 and screwed into these apertures are the stems 69 of valve housings 70 having openings 71 at their tops surrounded 25 and each of these stems 74 carries a float 75, the stem 74 being engaged through the float as shown. A nut 76 is fixed to the float and is in threaded engagement with the stem 74 so that by holding the float still and 30 rotating the stem the elevation of the float may be changed. Another nut 77 is threaded upon the stem above the float and between this nut and the float there are a plurality of preferably metallic washers 78, the 35 nut 77 being bodily removable from the stem to permit of the removal or addition of washers. The circumstances under which a change in washers is made and the purpose thereof will be presently brought out.

45 From the foregoing description of the valve arrangement it will be seen that the level of fluid in the different compartments 18, 19 and 20 is controlled by the floats 75, it being understood that fuel supply pipes 50 79 are connected with the openings 65 of the bowl.

As shown in the drawings, the connection of the present carbureter with an engine is through the lateral extension 45' of the dome 45, and that the air intake is through the upper end of the tube 43 which may be provided, as shown, with a hot air intake pipe 80 leading to a point near the exhaust manifold of the engine.

60 In use, it is designed to connect the compartment 18 with a gasoline supply, the compartment 20 with a kerosene supply and the compartment 19 with a water supply.

As brought out above, the fuel from the compartments 18 and 20 is carried to the gauze

tube 59 in the manner described and, when the engine is in operation, the incoming air passes down through the tube 43 picking up the particles of fuel from the gauze tube which is saturated therewith. Capillary attraction will cause the fuel to spread in thin films over the interstices of the gauze and will thus present the fuel to the incoming air in a manner in which it is most readily taken up by and combined with the 75 air. In view of the fact that the gauze tube is engaged at its lower end with the inner face of the dome, a greater portion of the air which passes into the engine, must pass through gauze and thus an effective combination of the fuel and air is brought about. The advantage of supplying moisture to a carbureter is well known and with the compartment 19 containing water, the latter is also supplied to the gauze tube, the quantity 80 thereof being controlled by the needle valve 63 and since water is heavier than either of the hydrocarbons to be used in this carbureter, the water will not be sucked from its duct until the engine is working in a 85 manner to create a considerable vacuum. By a regulation of the float valve in the water chamber in conjunction with the needle valve, the vacuum necessary to feed water to the engine can be properly regulated. 95

In the foregoing reference was made to a vane 58 carried by the sleeve 54 which controls the auxiliary air supply of the present carbureter. In use, it is designed to place 100 the carbureter upon the engine in such position that its vane will lie in the air blast from the cooling fan C of the engine. Thus when the engine is running at high speed and additional air is necessary, the cooling 105 fan will be driven at high speed, and the air blast having correspondingly greater force will impinge upon the vane 58, moving the latter and moving therewith the sleeve 54 against the action of the spring 57 to bring 110 the openings 53 and 56 into registration and permit the passage of extra air into the engine through the course brought out above.

In Fig. 7 there is shown a modified form of auxiliary air valve of a type similar to 115 that usually employed in carbureters. In this form of the invention the tube 43 has a sleeve 81 engaged therewith, this sleeve being similar to the sleeve 49, and carrying a hollow circular body 82 at its lower end 120 similar to the flange 50 but of considerably greater thickness. At the upper end of this body there are openings 83, and within the body there is a seat 84 adapted to receive an annular valve 85 engaged around and working upon the upper portion of the tube 43 and held against its seat by a spring 86 disposed between the valve 85 and the top plate 13.

In the foregoing it is stated that there are 130

1 a plurality of preferably metallic washers 78 disposed upon each of the float valves and that these washers are removable. The 5 purpose of this provision is to make it possible to so weight the floats by means of the washers as to assure the proper opening and closing of the ball valves. If the column 10 of liquid leading to a given float valve should exert more pressure against the valve than would be overcome by the weight of the float and its washers, additional washers can be added until the desired result is attained.

What is claimed is:—

15 1. A carbureter including a bowl, a web disposed within the bowl to form two compartments, a sleeve within the bowl disposed with its passage opening exteriorly of the bowl at both ends, said web having a 20 horizontal chamber therewithin opening through the outer face of the bowl and communicating at its inner end with the interior of the sleeve, an air conducting member disposed within the sleeve and having an 25 opening registering with the chamber to receive fluid therefrom, said web having vertical valve chambers formed therein and opening through its top and having also passages leading one from each of said valve 30 chambers to the bowl compartments respectively, said web also having ducts formed therein and leading from the valve chambers to the horizontal passage, valves in the valve chambers arranged for operation to open 35 and close the ducts, and a needle valve disposed within the horizontal chamber of the web for operation to open and close the inner end of said chamber, said needle valve extending outwardly beyond the outer end 40 of said chamber.

2. A carbureter including a bowl having two compartments and a centrally located open ended sleeve formed therewithin, fluid conducting means communicating with the 45 compartments and with the interior of the sleeve, an air conducting tube engaged through the sleeve in spaced relation thereto and having an opening in close union with the fluid conducting means to receive fluid 50 into the tube, a vaporizing dome carried by one end of the tube and communicating both with the tube and with the sleeve exteriorly of the tube, means for controlling the admission of air to the space between the sleeve 55 and the tube, and means for controlling the supply of fluid from the compartments.

3. A carbureter comprising a bowl, a sleeve within the bowl disposed with its passage opening exteriorly of the bowl at both 60 ends, said bowl having two compartments therein, an air conducting member disposed within the sleeve in spaced relation to the

walls thereof, means for controlling the passage of air through the space between the sleeve and the air conducting member, means 65 for conducting air from both the air conducting member and the space between the air conducting member and the sleeve to an engine, and means for conducting fluid from the two compartments to the interior of the 70 air conducting member.

4. A carbureter having an angularly disposed carbureted air duct, an inlet and mixing tube leading to said duct and provided at its end with a spreading cone, and a gauze 75 tube lining said inlet and resting at one end on the wall of the duct to close said tube end, said carbureter having an auxiliary air passage surrounding said inlet tube and communicating with said duct. 80

5. A carbureter including a bowl having a web therein disposed to form two compartments, said web having separate valve chambers therein and having also a passage communicating with each valve chamber and 85 with one of the compartments, an air conducting member associated with the bowl, said web having a passage formed therethrough and communicating with the interior of the air conducting member, said web also having a passage communicating with each of the valve chambers and with the passage which communicates with the air conducting member, a valve for each valve chamber, said valves being arranged for movement into 90 and out of position to close the passages which lead to the compartments, means for operating the valves oppositely, and means for controlling the flow of fluid through the passage which communicates with the air 95 conducting member. 100

6. A carbureter including a bowl, a web disposed within the bowl to form two compartments, said web having separate parallel vertical valve chambers formed therein, 105 a passage communicating with each of the chambers and with one of the compartments, an air conducting member associated with the bowl, a horizontal passage communicating with the air conducting member a valve 110 in each valve chamber, said valves being movable into and out of position to close the first mentioned passages, an upwardly extending passage communicating with each of the valve chambers and with the horizontal 115 passage, and means for controlling the flow of fluid from the horizontal passage or the air conducting member.

In testimony whereof, I affix my signature, in the presence of two witnesses.

EDWARD A. STINSON.
